United States Patent Office

Des. 196,503
Patented Oct. 8, 1963

196,503

SEAM RIPPER OR THE LIKE

Percy Seymour Hargrave Leafe, Ealing, England, assignor
of one-half to Needle Industries Limited, Birmingham,
England, a British company

Filed June 26, 1962, Ser. No. 70,696

Claims priority, application Great Britain Mar. 16, 1962

Term of patent 14 years

(Cl. D22—3)

FIGURE 1 is a perspective view of a seam ripper or the like showing my new design;

FIGURE 2 is an enlarged fragmentary side elevational view of the blade;

FIGURE 3 is an enlarged sectional view taken on the line III-III of FIGURE 2.

FIGURE 4 is a perspective view of the side opposite that shown in FIGURE 1.

FIGURE 5 is a top plan view thereof, and

FIGURE 6 is a bottom plan view thereof.

I claim:

The ornamental design for a seam ripper or the like, substantially as shown.
